TRUCK

Carl F. Collins, Winterhaven, Fla.

Application June 13, 1934, Serial No. 730,406

12 Claims. (Cl. 214—65.5)

This invention appertains to hand trucks employed in warehouses and the like for handling containers of various characters, the truck being of the type embodying an elongated frame terminating in handles at one end and supporting ground wheels at its opposite ends, with means adjacent to the wheels for engaging under the load to be carried.

One of the salient objects of my invention is to provide a hand truck having novel adjustable means at its forward end for engaging under and clamping the load, whereby tiers of boxes of varied sizes can be conveniently and expeditiously handled.

Another important object of my invention is to provide a hand truck having laterally extending gripping arms at its forward end, with means on the arms for engaging under the load, novel means being provided for adjusting the arms toward and away from one another, whereby different sizes of containers can be readily grasped.

A further object of my invention is to provide supplemental and forcible means for urging the arms into clamping contact with the load after the first adjustment of the arms to insure against the slipping of the load, said supplemental means being also operable to facilitate the initial releasing of the arms from the load, whereby the first adjusting means can be conveniently operated.

A further object of my invention is to provide a swinging platform on the body of the truck, with novel means for adjusting the platform toward and away from the gripping arms, whereby relatively thin boxes can be conveniently gripped by said arms and supported on the truck.

A further object of my invention is to provide novel means for releasably locking the platform in its adjusted position, whereby the same will firmly support the load when the truck is tilted back to its carrying position.

A further object of my invention is to provide novel means for mounting the various operating parts on the truck, whereby the same can be conveniently actuated by the user of the truck, and whereby such mechanism will be out of the way of the load to be carried.

A still further object of my invention is to provide a novel hand truck of the above character, which will be durable and efficient in use, one that will be simple and easy to manufacture, and one which can be placed upon the market at a reasonable cost.

With these and other objects in view, the invention consists in the novel construction, arrangement, and formation of parts, as will be

hereinafter more specifically described, claimed, and illustrated in the accompanying drawings, in which

Figure 1 is a side elevation of a hand truck constructed in accordance with my invention;

Figure 2 is a front elevation of the same;

Figure 3 is an enlarged fragmentary longitudinal sectional view of the truck, taken on the line 3—3 of Figure 2, looking in the direction of the arrows, illustrating the novel means employed for adjusting the position of the platform.

Figure 4 is a detail horizontal section through the frame of the truck and platform at one side, the view being taken substantially on the line 4—4 of Figure 3;

Figure 5 is a fragmentary rear elevation of the supporting platform showing the actuating means carried thereby;

Figure 6 is an enlarged detail view of the operating handle for the platform;

Figure 7 is an enlarged rear elevation of the housing for the operating means of the clamping arms with the cover plate removed to illustrate such operating mechanism, one of the arms and its operating mechanism being omitted to simplify the understanding of the operating mechanism, the arm being shown in its extreme closed position;

Figure 8 is a horizontal section taken substantially on the line 8—8 of Figure 7, looking in the direction of the arrows, illustrating the operating mechanism for both of the arms;

Figure 9 is a horizontal section taken on the line 9—9 of Figure 7 looking in the direction of the arrows, the arms being shown in their extreme closed position;

Figure 10 is a vertical section taken substantially on the line 10—10 of Figure 7, looking in the direction of the arrows;

Figure 11 is a view similar to Figure 7 showing the arm in its extreme open position.

Referring to the drawings in detail, wherein similar reference characters designate corresponding parts throughout the several views, the letter "A" generally indicates a hand truck constructed in accordance with my invention, and which embodies a pair of spaced parallel side beams or rails 15. The rear ends of the rails 15 are suitably treated to provide hand grips 16. The rails are also connected together in any preferred manner, such as by cross-braces 17. Suitably secured to the forward ends of the side beams or rails 15 are wheeled brackets 18, and

any preferred type of ground wheels 19 can be journaled in said brackets. Likewise, rigidly secured to the side beams or rails 15, adjacent to their forward ends, is a housing or casing 20, which encloses the operating mechanism 21 for the gripping arms 22 and 23. These arms have their inner ends extended into the casing through the opposite side walls thereof, and sleeves 24 are carried by the side walls of the casing for receiving said arms. These guide sleeves can also be extended through the side rails or beams 15 of the truck frame and through the wheel brackets 18. If desired, other guides 25 can be arranged interiorly of the casing for said arms. These arms 22 and 23 project laterally beyond the sides of the truck frame, and have formed thereon forwardly projecting wings or legs 26. The inner faces of the legs or wings 26, at their forward ends, carry spurs 27 which are adapted to engage under the load. These spurs are adapted to be formed from hardened metal and can be detachably connected with the arms so that the same can be replaced when worn. The novel mechanism 21 is employed for moving the arms and spurs 27 toward and away from one another to grip the load to be carried, and this means will be later described in detail.

In order to provide for the carrying of relatively thin boxes, and to permit the convenient gripping thereof by the arms and spurs, I employ an adjustable platform 28, which is movable towards and away from the spurs 27. This platform 28 is carried by the frame of the truck between the side beams 15 thereof. The supplemental platform 28 also includes longitudinally extending side rails 29, which are preferably formed from channel iron. The side beams 29 can be connected at spaced points by transverse brace strips 30. The inner or rear ends of the side rails 29 have formed thereon, or secured thereto, hinge barrels 31 which receive supporting pintles 32. The pintles 32 are firmly and rigidly secured to the side truck beams 15. The lower end of the supplemental platform is left free for swinging movement and the novel means employed for moving this end of the platform towards and away from the spurs 27 includes a transversely extending rock shaft 33. The rock shaft 33 is carried in bearing brackets 34 welded or otherwise secured to the side frame pieces 29 adjacent to their rear ends. Keyed to the rock shaft 33 adjacent to one end thereof is a crank arm 35, and a crank handle 36 is keyed or otherwise secured to the shaft 33 adjacent to its other end. Pivotedly secured to the crank 35 and the handle crank 36, are links 37 and 38. These links 37 and 38 extend in rear of the side frame pieces 29 and the extreme lower ends thereof carry headed guide pins 39. The heads of the guide pins are slidably mounted in channel-shaped guides 40, which are secured to the side truck frame beams 15, and it is to be noted that the channel guides 40 extend parallel with said beams. Rigidly secured to, or formed on the side frame pieces 29 adjacent to their forward ends, are rearwardly directed plates 41, having diagonally extending slots 42 formed therein. The body portions of the guide pins extend through the slots 42.

From the description so far, it can be seen that when the hand grip of the hand crank 36 is grasped and is swung downwardly, the rock shaft will be rotated, and the links 38 will be pushed downwardly. Due to the connection between the

pins 39 and the guides 40, the lower ends of the links will move in a straight downward path, and as the pins 39 follow this path, the same, riding against the inclined walls of the slots 42 will push the supplemental platform forwardly. Means can be provided for locking the hand crank or lever in an adjusted position when the platform is in its extreme raised or tilted position. This means may consist of a hand lever 43 rockably mounted intermediate its ends on a pivot pin 44 carried by the hand crank 36.

Secured to the hand lever 43 at one side of the pivot 44, is a lock pin 45, which extends through the hand crank. The opposite side of the hand lever 43 is engaged by a contractile coil spring 46, which normally functions to urge the pin 45 through the hand crank. The end of the hand lever 43, remote from the spring, is shaped to constitute a handle 47, and the same lies adjacent to the hand grip of the hand crank. Thus, by gripping the handle 47 and the hand grip or crank, the lever can be rocked to cause the movement of the pin 45 inwardly.

When the hand crank 36 is in its extreme lowered position (see Figure 5) the pin will register with a lock opening 48 in the link 38, and can ride into the same. This will effectively lock the mechanism against movement.

Referring specifically to the operating mechanism 21 for the arms 22 and 23, it will be noted that a pair of spaced parallel guide bars 50 are rigidly secured in the casing 21 adjacent to its upper end. These guide bars 50 have slidably mounted thereon rack bars 51. The rack bars 51 carry guide loops 52 for receiving the guide bars and depending from the loops are converging arms 53 which rockably support at their point of connection a double ended operating lever 54.

One rack bar, and its dependent ended lever 54, operate one of the clamping arms and the other rack bar and its double ended lever actuate the other gripping or clamping arm, and the mechanism for actuating both arms is identical, and hence only one will be described in detail.

It is to be noted, however, that below the guide bars 50 are a pair of spaced parallel similar guide bars 55 on which are slidably mounted carriages 56. Each of the carriages 56 carries depending lugs 57, and these lugs are rigidly secured to their respective arms 22 or 23. Each of the carriages 56 is provided with vertically slotted heads 58. The upper arm of the double ended lever 54 carries a pin 59 which is slidably received in the slotted head. The lower end of the double ended lever is pivotally connected by means of a pin 60 with the link 61 of a toggle 62. The other link 63 of the toggle is pivotally connected as at 64 to a rigid bar 65 of the casing at one side. The pivot pin 66 is employed for pivotally uniting the links 61 and 63 of the toggle 62 together.

Rotatably extending through the top wall of the casing 20 is an operating shaft 67, and the inner end of this shaft has keyed or otherwise secured thereto a pinion 68, the teeth of which engage the teeth of the rack bars 51. Obviously, upon rotation of the pinion, the rack bars will be caused to move in opposite directions and carry their respective double ended levers 54 together.

The operating shaft 67 extends longitudinally of the truck frame and rearwardly a sufficient distance to be conveniently operated by the hand of the user of the truck. A manipulating handle 76

69 is carried by the shaft, and if preferred, a pawl and rigid mechanism can be had between the handle and the shaft, and means can also be provided for locking the shaft against rotation 5 after preferred adjustment of the clamping arms.

From the description so far it can be seen that when the shaft 67 is rotated and the rack bars are moved in opposite directions, say towards one another, the levers 54 will be carried 10 toward one another.

Referring to Figure 7, as the lever 54 moves to the right, the same will be swung on the pivot 60 and on the pivot carried by the converging arms 53 of the rack bar 51. Hence, the upper 15 end of the lever 54 will be swung to the right, and the same will carry the carriage 56 to the right. Due to the connection between the carriage and its arm, the arm will be moved outwardly. Obviously, the same action simultaneously takes place to the other arm.

I utilize the intermediate mechanism between the rack bars and the arms so that a forcible and augmented leverage will take place.

It is also one of the salient features of my 25 invention to provide a supplemental means other than that described for giving an additional adjustment movement to the arms 22 and 23. This supplemental mechanism is utilized for initially releasing the load and for gripping and clamping 30 the load after the arms have been adjusted to the desired position and brought around the load to be carried.

By using the supplemental adjusting mechanism the arms can be forcibly brought into contact with the load and the spurs 27 moved under the load. The supplemental adjusting mechanism for the arms is generally indicated by the reference character 70 and includes an operating rock shaft 71. The rock shaft extends transversely through the casing 20 adjacent to one upper corner thereof, and is journaled in bearings carried by the casing. This shaft is also supported by the guide bars 50, and the shaft extends through these guide bars. Keyed to the shaft, or rigidly secured thereto in any other desired way, are cranks 72 and 73. These cranks are preferably formed on sleeves, which are secured to the rock shaft, and the sleeves extend respectively between the cover plate of the casing and one guide bar 50, and between both the guide bars 50.

Secured to the outer end of the shaft 71 is an operating foot lever 74 which is preferably of a bell crank shape. The opposite ends of the foot lever 74 have formed thereon, or secured thereto, foot pedals 75. Pivots connected to the crank 72, by means of a pivot 76 is a connecting link 77. This link 77 is pivotally connected by means of a pin 78 with a crank 79 keyed or otherwise secured to a rock shaft 80. The rock shaft 80 is similar to the rock shaft 71 and functions in the same manner. The rock shaft 80 is also journaled in the walls of the casing 20, and extends through the guide bars 50. At a point spaced 65 from the crank 79 is a crank 81, which is also keyed to the rock shaft 80, the crank 81 is similar to the crank 73 and these two cranks 73 and 81 have pivotally connected thereto depending operating links 82 which extend down to their respective toggles 62.

By referring to Figures 7 and 11, it can be seen that the operating links 82 are pivotally connected to the toggle links 63 adjacent to their pivots 66.

Considering that the arms 22 and 23 have been

initially adjusted, and it is desired to extend the same outwardly a further distance, so that when the arms are placed around the load, the arms can be moved into a clamping position, the outer end (see Figure 7) of the foot lever is pressed downwardly. This will move the parts to the position shown in Figure 11, and this movement is accomplished in the following manner.

The rock shafts 71 and 80 will be turned in unison due to their connection by the link 77. 10 Hence, the cranks 81 and 73 will be swung upwardly. This will move the operating links 82 upwardly and break the toggles 62. The breaking of the toggles functions to draw inwardly on the lower end of the double-ended lever 54 and 15 swing the upper end thereof outwardly, moving the carriage 56 and its arm outwardly. Obviously, when it is desired to contract the arms, the inner foot pedal is pressed downwardly, which will function to straighten out the toggle and 20 slide the carriages and arms inwardly.

From the description so far, it is apparent that when the truck is to be utilized for carrying a load, the arms 22 and 23 are adjusted to the width of the box or other container to be handled, and the supplemental adjusting means is actuated to open the arms. The truck is now elevated on its wheels 19 and the truck is pushed forwardly so that the forwardly extending portions or legs 26 of the arms will lie on opposite 30 sides of the box. If desired, the arms can be moved inwardly by the shaft 67 until the spurs engage the load. The supplemental adjusting means can now be actuated to forcibly urge the spurs under the load, and the forwardly extending portions 35 26 of the arms into contact with the load. By tilting the truck back on the wheels the load can be swung back on the truck.

While the present invention has been illustrated and described in connection with hand trucks, it is to be understood that certain features of the same, such as the clamping mechanism, are equally applicable to conventional power trucks, and to that extent the invention hereinafter claimed is not to be specifically limited 45 to hand trucks, but is contemplated to include power trucks, as regards such features applicable thereto.

Changes in details may be made without departing from the spirit or the scope of my invention, but what I claim as new is:—

1. In a hand truck comprising a wheeled frame, a pair of slidable arms on the frame, movable towards and away from one another, a sliding rack bar for each arm, means including a shaft and pinion for simultaneously operating the rack bars towards and away from one another, a double ended lever rockably mounted intermediate its ends on each rack bar, a sliding carriage for each arm, means connecting the carriage with its arm, a pivot for the lower end of each double ended lever, and a pin and slot connection between the upper end of the levers and carriages.

2. In a hand truck comprising a wheeled frame, 65 a pair of slidable arms on the frame, movable towards and away from one another, a sliding rack bar for each arm, means including a shaft and pinion for simultaneously operating the rack bars towards and away from one another, a 70 double ended lever rockably mounted intermediate its ends on each rack bar, a sliding carriage for each arm, means connecting the carriage with its arm, a pivot for the lower end of each double ended lever, a pin and slot connection between 75

the upper end of the levers and carriages, and means independently of the rack bars for changing the angle of the double ended levers.

3. In a hand truck, a wheeled frame, a pair of arms slidably mounted on the frame and movable towards and away from one another, a pair of rack bars movable towards and away from one another, means for simultaneously operating the rack bars in opposite directions, a double ended lever rockably supported intermediate its ends by each rack bar and movable therewith, a sliding carriage for each arm, means rigidly connecting the carriages with their arms, a pin and slot connection between the upper ends of the double ended levers and the carriages, a toggle for each carriage, each toggle including a swinging short link and a long link, the short and long links being pivoted together, means pivotally connecting the lower ends of the double ended levers to the outer ends of the long links of their toggles, and means for straightening and breaking the toggles.

4. In a hand truck, a wheeled frame, a pair of arms slidably mounted on the frame and movable towards and away from one another, a pair of rack bars movable towards and away from one another, means for simultaneously operating the rack bars in opposite directions, a double ended lever rockably supported intermediate its ends by each rack bar and movable therewith, a sliding carriage for each arm, means rigidly connecting the carriages with their arms, a pin and slot connection between the upper ends of the double ended levers and the carriages, a toggle for each carriage, each toggle including a swinging short link and a long link, the short and long links being pivoted together, means pivotally connecting the lower ends of the double ended levers to the outer ends of the long links of their toggles, means for straightening and breaking the toggles, said means including a pair of rock shafts, cranks on the rock shafts, depending operating links secured to the cranks and to the short links of the toggles, a foot pedal for operating one of said shafts, and means operatively connecting the shafts together.

5. A hand truck comprising a wheeled frame, a pair of arms slidably carried by the lower end of the frame and movable towards and away from one another, means for adjusting the arms, forwardly extending legs carried by the arms, inwardly directed spurs on the legs, and a platform on the truck frame movable towards and away from the spurs.

55 6. A hand truck comprising a wheeled frame, a pair of arms slidably carried by the lower end of the frame and movable towards and away from one another, means for adjusting the arms, forwardly extending legs carried by the arms, inwardly directed spurs on the legs, a platform on the truck frame movable towards and away from the spurs, and manual means for adjusting the position of the platform.

65 7. A hand truck comprising a wheeled frame, a pair of arms slidably mounted on the frame, means for moving said arms toward and away from one another, forwardly directed legs on the arms and spurs on said legs projecting towards one another, a platform for the truck frame, means pivotally connecting the upper end of the platform to the truck frame, means for swinging the lower end of the platform towards

and away from the spurs, said means including a rock shaft carried by the upper end of the platform, cranks secured to the rock shaft, a hand grip on one of said cranks, depending links pivotally secured to the cranks, channel-shaped guides secured to the truck frame, plates carried by the sides of the platform adjacent to its lower end having diagonally extending slots therein, and headed pins carried by the forward ends of the links, received in said slots with the heads thereof mounted in said guides.

8. A hand truck comprising a wheeled frame, a pair of arms slidably mounted on the frame, means for moving said arms toward and away from one another, forwardly directed legs on the arms and spurs on said legs projecting towards one another, a platform for the truck frame, means pivotally connecting the upper end of the platform to the truck frame, means for swinging the lower end of the platform towards and away from the spurs, said means including a rock shaft carried by the upper end of the platform, cranks secured to the rock shaft, a hand grip on one of said cranks, depending links pivotally secured to the cranks, channel-shaped guides secured to the truck frame, plates carried by the sides of the platform adjacent to its lower end having diagonally extending slots therein, and headed pins carried by the forward ends of the links, received in said slots with the heads thereof mounted in said guides, and means for locking the platform in an adjusted position.

35 9. An operating mechanism comprising a casing, members slidably mounted in the casing, a pair of rack bars in the casing, means for simultaneously moving the rack bars towards and away from one another, a carriage slidably mounted in the casing for each member, means rigidly connecting the carriage with its member, a double ended lever rockably supported intermediate its ends by each rack bar, means pivotally supporting the lower end of each lever, and a pin and slot connection between the other end of each lever, and a carriage.

40 10. A hand truck comprising, a wheeled frame, gripping jaws slidably mounted on the frame and movable toward and away from one another, a rack bar for each arm, means for simultaneously operating the rack bars in opposite directions, and an intermediate leverage mechanism operatively connecting the rack bars with the sliding gripping arms to increase the power on said arms.

45 11. A hand truck comprising, a wheeled frame, a pair of gripping arms carried by the lower end of the frame and movable toward and away from one another into and out of load gripping position, means for adjusting the position of the arms, and a platform on the truck frame movable between the arms toward and away from the forward ends thereof.

50 12. A hand truck comprising, a wheeled frame, a pair of gripping arms carried by the lower end of the frame and movable toward and away from one another, means for adjusting the arms into and out of load gripping position, a swinging platform on the truck frame movable between the arms toward and away from the forward ends thereof, and manual means for adjusting the position of the platform.
